UNITED STATES PATENT OFFICE.

DAVID JOHN CHAPPELL, OF LLANELLY, WALES.

AIR TUBE FOR PNEUMATIC TIRES.

Application filed May 11, 1922. Serial No. 560,224.

To all whom it may concern:

Be it known that I, DAVID JOHN CHAPPELL, a subject of the King of Great Britain and Ireland, of 52 College Hill, Llanelli, 5 South Wales, Great Britain, have invented a new and Improved Air Tube for Pneumatic Tires (for which I have filed application for patent in Great Britain No. 1784, filed 11th January 1921), of which the following is a specification.

This invention relates to improvements in pneumatic tubes for automobile tires, the object of the invention being to effect improvements in the construction of the tube 15 whereby the same will be prevented from becoming deflated in the event of a puncture.

With the above and other objects in view, the invention consists in the construction, combination and arrangement of the devices as hereinafter described and claimed.

In order to enable my present invention to be fully understood reference will be made to the accompanying drawings illustrating the same.

25 Figure 1 is a plan and Figure 2 is a section (on line X—X) of a portion of the length of one of the strips.

Figure 3 is a plan and Figure 4 is a section (on line Y—Y) of a portion of the 30 length of a number of the strips when laid properly in position overlapping one another.

Figure 5 is a perspective view of a broken piece of air tube, showing a part of its 35 inside surface covered with the strips properly arranged as in Figure 3.

Figure 6 is a plan (similar to Figure 1) of a modified form of strip.

Fig. 7 is a sectional perspective view of 40 the same.

Referring to Figures 1 to 5, not only is each strip *b* slotted at *b*¹ to produce flaps *b*², but in keeping with my present invention, tongues *c* are provided upon the flaps 45 *b*² for covering the slits *b*¹ in the strip which

is underneath. Each slit *b*¹ is therefore completely covered by a tongue which is free at one end, belonging to the next strip *b*, above, and there is, or there should be preferably, no slit throughout the whole 50 protective surface left uncovered by one of the tongues *c*. When therefore a nail *d* (Figure 5) happens to puncture the air tube *a* at a point opposite one of the innumerable slits *b*¹, it will simply lift up the tongue *c* 55 covering that slit without puncturing the tongue, and the tongue *c* will seal the puncture when the nail *d* is withdrawn.

The free ends of the tongue *c* may project beyond the open ends of the slits *b*¹ if this 60 should be found to be any advantage. Moreover tongues *c* may be either of the same length as the slits *b*¹ or shorter or longer, according to wish. The slits *b*¹ may be formed of any width, either as shown in 65 Figure 6, or of any greater width not larger than the width of the tongues *c* which are intended to cover them.

My invention is not confined to rectangular forms such as illustrated, as the tongues 70 and slits or gaps may be formed in any other suitable shape. In any particular case where it may be found desirable, the strips, that is the flaps and tongues, may be treated with glycerine or any other serviceable medium 75 to render them tacky, sticky or otherwise more air proof along the surfaces or edges which are normally in contact with one another.

I claim:

An improved air tube for pneumatic tires of the kind having strips of thin rubber or equivalent material fastened along one edge to its inner surface such strips overlapping each other and each strip cut into 85 flaps, characterized by the flaps each having a tongue or extension sufficiently long and wide to cover completely the slits or gaps in the next strip below.

DAVID JOHN CHAPPELL.
